UNITED STATES PATENT OFFICE.

CURTIS WHITEHALL, OF NEWTOWN, INDIANA.

CULTIVATOR.

SPECIFICATION forming part of Letters Patent No. 330,761, dated November 17, 1885.

Application filed July 14, 1885. Serial No. 171,634. (No model.)

To all whom it may concern:

Be it known that I, CURTIS WHITEHALL, of 5
Newtown, in the county of Fountain and State
of Indiana, have invented certain new and
useful Improvements in Cultivators, of which
the following is a specification, reference be-
ing had to the accompanying drawings, in
which—

Figure 1 is a perspective view of a culti- 10
vator embodying my improvements. Fig. 2
is a vertical longitudinal section. Fig. 3 is a
vertical transverse section, and Fig. 4 is a de-
tail.

Similar letters indicate similar parts in the 15
respective figures.

My invention consists in so constructing
and combining the several parts of a culti- 20
vator as to give greater control over the plows,
to lighten the weight of the cultivator on the
horse, and to make the draft easier, as will be
hereinafter explained.

In the drawings, A A are the axles, to
which the wheels a are attached in the ordi- 25
nary way.

25 B is the arch of the cultivator, which is
formed of the same piece of metal as the axles,
but situated forward of the line of the axles.
This is accomplished by bending the axle at
30 a right angle forward in a horizontal line, as
shown at c, to the required distance, then
bending it at a right angle on the same line
toward the center of the cultivator, as shown
at b, then at a right angle perpendicularly to
35 the proper height to form the arch, and so
on to make both sides alike.

Fig. 4 shows in perspective the axles and
arch detached from the cultivator.

To the outer side of each of the parts c is
40 secured a block, d. These blocks d are perfor-
ated to allow the axle A to pass through
them and extend forward a sufficient distance
to allow the attachment thereto of the com-
pound evener, as will be hereinafter ex- 45
plained.

45 D is the tongue, which is divided at its
rear end, forming a fork, C C, as shown. The
rear ends of the fork C C are connected to the
axles A by means of the braces e. The arch
B extends up inside the fork C C, and is at- 50
tached to it on each side by means of the eye-
bolts f, the sides of the arch fitting loosely in
the eyes of the bolts, thus enabling it to have
a vertical movement independently of the fork
or tongue.

E is a block connecting and bracing the two 55
sides C of the fork.

F is a bar, which is centrally pivoted to the
block E at g, and which extends on each side
of the tongue to a distance about on a line 60
with the blocks d. At each end of the bar F
is suspended a rod, G, which rods G are each
connected to one of the blocks d by means
of a hook, H. The bar F, rods G, hooks H,
and blocks d constitute the compound evener 65
before mentioned. The rods G are perfor-
ated at i, these perforations being for the
purpose of attaching the single-trees.

I are plow-beams, the front ends of which
pivot to b, thus bringing the points of the
beams forward of the axles and on a line with 70
the arch.

J J are hooks attached to the fork C for the
purpose of holding the plow-beams I I up
when not in use.

The advantages of my construction are as 75
follows, viz: By attaching the plow-beam at
a point forward of the axle, and by so con-
necting the arch to the tongue as to allow the
arch to have an independent vertical move- 80
ment, the operator has greater control over
the plow, inasmuch as the rising and falling
movement of the wheels, caused by uneven
ground, will not be communicated to the plow-
beams, and thus the jerking motion of the 85
plows will be obviated. It will also be seen
that when the plow-beams are hung on the
hooks J the weight of the plow is thrown al-
most directly upon the wheels, thus taking it
off from the tongue and relieving the necks 90
of the team. The hitching is also more di-
rectly on a line with the hame-hook, thus giv-
ing greater ease to the team, and at the same
time better control over the tongue.

Having described my invention, I claim—

In a cultivator, the axles and arch A B, 95
formed of one piece of metal, combined with
the braces e, forked tongue C D, and the
compound evener consisting of the blocks d, bar
F, rods G, and hooks H, substantially as set
forth.

In testimony whereof I have hereunto set
my hand and seal this 22d day of June, A. D.
1885.

CURTIS WHITEHALL. [L. S.]
